WAISTBAND

Application filed September 1, 1926. Serial No. 132,978.

The invention is an improvement in waist bands and methods of making the same, and relates more particularly to bands designed for use with trousers.

5 As a rule, clothing manufacturers prefer to purchase waist bands assembled and in condition to be attached directly to the garment. Hence a desirable form for the waist band lining is in suitable lengths, from which a 10 number of individual pieces of suitable size for a garment may be cut.

For the sake of economy, the bands are attached by machine sewing, and it is desirable that in the finished garment the attachment 15 simulate hand sewing. To attain this result the finish of the band should be such that when attached to the garment, it will give the appearance of a hand sewed band, irrespective of the machine sewing, and without the 20 cooperation thereof.

It is evident that a band so constructed must be attached to the garment in a predetermined manner, and along predetermined lines, otherwise the effect of hand sewing inherent in the band and independent of the attaching thread will not appear to the best advantage, and the desired finish of the garment 25 will not be attained.

In order that the band may be so attached, 30 it is desirable that there be a guide in connection with the band for the operator in running the seam, since slight deviations from the predetermined line of attachment will result in unsightly breaks or failures in 35 the hand sewing effect.

One of the primary objects of the present invention is the provision of a waist band, by means of which properly positioned with 40 respect to the garment and machine sewed in place, the appearance of a hand finished garment may be attained.

Another object is the provision of a band which may be attached to the garment with a 45 minimum of labor and by the usual method.

Another object is the provision of a band composed of assembled strips of stiffening material and lining so constructed that when superposed upon the garment in a predetermined manner, it will present a guide for the

proper running of the seam which is to connect the band to the garment.

Another object is the provision of a band constructed as above described, in which the parts occupy the relative position they will 55 occupy in the completed garment, and are biased to reassume such relative position when disarranged during the attachment of the band to the garment.

Another object is the provision of a band of 60 the character specified with a hem at one edge formed by turning over the edge of the band, and wherein the turned over edge is so connected to the band, that when said edge is 65 straightened into substantially the plane of the band the display face of the band will present a rib, and the obverse face a crease, indicating the location of the seam for connecting the band to the garment.

Another object is the provision of a band of 70 a nature such that it easily may be used for replacement in finished garments.

With these and other objects in view the invention consists in the method and in the construction and novel combination of parts 75 fully described hereinafter, illustrated in the accompanying drawings, and pointed out in the claims appended hereto, it being understood that various changes in the form, proportion, size and minor details of construction within the scope of the claims, may be resorted to without departing from the spirit 80 of the invention.

In the drawings forming a part hereof:

Fig. 1 is a plan view of the completed band, 85 looking at the obverse face.

Figs. 2, 3 and 4 are transverse sections of the band showing the method of making the same.

Figs. 5 and 6 are similar views of the band 90 and trousers material illustrating the manner of attaching the band.

Fig. 7 is a plan view of the band in place.

Fig. 8 is a plan view of the band with the turned over edge straightened into substantially the plane of the band, and showing the indicating line of a contrasting color for the attaching seam.

The improved band is composed of a strip 100 1 of a suitable stiffening material, such as

canvas, buckram or the like, and a strip 2 of lining material of a suitable character. The strip 2 is of greater width than the strip 1, the excess width being sufficient to provide for a turn-over or hem 3 at one edge 5 of the completed band, when the opposite edges of the strips 1 and 2 are in substantial register.

In connecting the parts, one edge of the strip 2 is superposed upon an edge of the strip 1, over a width corresponding to the excess 3 in width of the strip 2 over the strip 1, and the strips are connected by a line 4 of stitching. This line is at or near the edge 15 of the strip 2, and spaced apart from the edge of the strip 1 a distance corresponding substantially to the excess width of the strip 2. The strip 2 is now folded over about the edge of the strip 1, as indicated in Fig. 3, 20 providing thus at one edge of the band a hem.

The opposite edges of the strips are in substantial register, and these edges are connected by a line of stitching indicated at 5. 25 This stitching is done upon a machine which turns over the edges of the two strips together upon the upper face of the stiffening strip, and secures them together through the turned over edge. The turning over of the edges 30 forms a crease between the turned over edge and the body of the band, and the parts are held in this position, and biased to reassume the same position when straightened into substantial alinement, by the stitching, which 35 is close to the junction between the turned over part and the body of the band.

It will be obvious that because of the stitching, when the parts are straightened in substantial alinement, a rib will appear on the 40 display face of the band, and a groove on the obverse face at the stitching. The line of stitching as clearly shown by the drawing is composed of two threads, one of which is in the form of inclined substantially parallel 45 stitches across or about the creased edge, while the other forms a line of straight end-to-end stitches on the inner face of the band.

So constructed the completed band as shown 50 in Fig. 4 is in the form of a length or ribbon, which may be of any convenient length, and may be marketed in this form. When the manufacturer wishes to attach a band, he cuts a suitable piece from the length. This 55 piece is superposed upon the garment, as for instance trousers, at the top, and on the outer surface, with the free edges of the turned over portion 6 of the piece in substantial register with the raw edge of the garment 7.

As previously pointed out, the method of connecting the turned over edge 6 to the body of the band provides on the obverse face a groove or crease, when the turned over edge 60 is straightened out into substantial alinement 65 with the body, and this crease or groove serves

as a guide for a line of stitching 9 to connect the band to the trousers.

It is desirable however that a guide be provided of a character more distinctly set off from the band, and more easily followed. 70 With this object in view a thread 10 of a contrasting color is arranged on the obverse face of the band at the bottom of the groove, the thread being held in place by the stitching 5 before mentioned. This thread is straight, 75 of a contrasting color, and is easily followed by the operator in placing the stitches 9.

After the band has been connected as above described, it is turned over upon the inner face of the garment material, the said material being creased at 11, so that the upper edge of the band is spaced slightly below the upper edge of the garment. That is the bend or finished edge at the top of the garment is provided by the trousers material. The inclined line of stitching above referred to is exposed at the top of the band, and since this line is composed of inclined substantially parallel stitches, it very closely simulates hand work. 85

It will be noticed that the stitching at the turned over edges of the strips is of a character such that while the edge is held flat upon the body, it is enabled to straighten into substantial alinement, yet it is biased by the stitching, that is inclined or influenced, to return to its normal position when free to do so. 90

What is claimed as new is:

1. As an article of manufacture, a length 100 of waist band material including a stiffening and a lining strip superposed one upon the other and arranged with their edges adjacent at one edge of the length, the said edge of the length turned over upon the stiffening strip to form a crease between the turned over edge and the body of the length, and stitching through and about the crease, the 105 crease forming a guide for the stitching of the band to a garment. 110

2. As an article of manufacture, a length of 115 waist band material composed of superposed stiffening and lining strips, one edge of the strips turned over upon the stiffening strip to form a crease between the turned over portion and the body of the band, said turned over portion secured to the body of the band by machine stitching at the extreme edge of the band and binding said edge, and a thread of a contrasting color in the crease and held 120 by the stitching of the edge. 125

3. As a new article of manufacture, a length of waist band material including connected stiffening and lining strips, the strips being arranged with the edges of the strips at one edge of the band adjacent and turned over upon the stiffening strip to form a bend, and machine stitching at and through the said bend connecting the turned over portion 130 of the lining strip to the stiffening strip and

to the body of the lining strip, and binding the bend, said stitching forming the sole connection between the strips at the said edge, whereby the remainder of the turned over portion is left free from the body of the band to enable said portion to be brought into substantial alinement with the body.

5 Signed at New York city, in the county of New York and State of New York, this 31st
10 day of August, A. D. 1926.
